Primary Examiner — Sheryl L Lane*Assistant Examiner* — Calvin E Vansant(74) *Attorney, Agent, or Firm* — RatnerPrestia(57) **CLAIM**

The ornamental design for a wheel for a motor vehicle, as shown and described.

DESCRIPTION

FIGS. 1 and 2 are front perspective views of a wheel for a motor vehicle;

FIG. 3 is a front elevation view thereof; and,

FIG. 4 is a top plan view thereof.

The color black indicates a color contrast and is not necessarily limited to any specific color.
